Attorney

UNITED STATES PATENT OFFICE.

KARL F. NYSTRÖM, OF CHICAGO, ILLINOIS.

FLOOR-RACK SUPPORT.

Application filed December 7, 1922. Serial No. 605,528.

To all whom it may concern:

Be it known that I, KARL F. NYSTRÖM, a subject of the King of Great Britain, and a resident of Chicago, in the county of Cook and State of Illinois, have invented certain new and useful Improvements in Floor-Rack Supports, of which the following is a description, reference being had to the accompanying drawing, which forms a part 10 of my specification.

My invention relates to a support for the floor racks of a refrigerator car, namely a support whereby the floor racks or superposed floor sections of a refrigerator car may 15 be supported or held in raised position and substantially parallel with the side walls of the car, while the car is being cleaned or at times when the car is not employed for refrigerating purposes and is intended to carry non-perishable merchandise requiring no 20 refrigeration.

The invention also has for its object the provision of supporting means whereby a smooth side wall surface is provided when 25 the racks are disposed parallel with the floor and the car is in use as a refrigerator car; namely a construction which eliminates the use of any projecting surfaces on the side walls of the car which would interfere with 30 or apt to injure the lading.

The objects and advantages of my invention will be readily comprehended from the detailed description of the accompanying drawing, wherein:

35 Figure 1 is a cross sectional view of a portion of a refrigerator car, with one section or rack in lowered or normal position, while the other section or rack is held in raised position by my improved supporting means.

40 Figure 2 is a detail sectional view of a portion of the main wall and floor of a refrigerator car and a portion of a rack, with my improved support shown in elevation and in rack-supporting position.

45 Figure 3 is a cross sectional view taken substantially on the line 3-3 of Figure 2 looking downwardly and also disclosing in dotted lines the position of the support when in non-supporting position.

50 Figure 4 is a detail view in elevation of a method of hinging the rack sections.

My invention is especially intended for refrigerator cars of the usual construction of properly insulated side walls 10 and floor 55 11. The floor is provided with a superposed rack as at 12; which is usually made in a

number of sections arranged lengthwise of the car and on each side of the longitudinal center line of the car in order that the various sections may be readily handled and also 60 independently raised and lowered out of and into operative position when desired.

The racks, of which any desired number commensurate with the size and length of the car may be employed, usually comprise 65 a suitable number of stringers or spacing members 13 on which the superposed runners or planks 14 are secured in spaced relation to permit circulation of the air currents beneath the racks and the lading or merchandise in the car and loaded on the racks to enable thorough refrigerating or cooling of 70 the merchandise.

In order that the car may be cleaned, it is 75 essential that the floor racks throughout the various portions of the car be removable from the floor and the same are therefore pivotally or hingedly supported to swing upwardly into parallel relation with the side walls of the car. For that reason each floor 80 rack or section is provided with a suitable number of hinges which are preferably of the construction more clearly shown in Figure 4, consisting of the bracket member 15 adapted to be bolted or secured onto the 85 floor proper of the car at a slight distance removed from the side walls thereof, while the adjacent stringer 13 of the rack in turn is provided with a somewhat similar bracket member 16 bolted or otherwise secured 90 thereto and arranged in lapping relation with the bracket member 15; the two bracket members being apertured to receive a pivot or hinge pin as at 17. The bracket members 15 and 16 are of such length as to permit the 95 same to be disposed beneath the runners or planks of the floor racks when the latter are resting on the main floor of the car, while at the same time permitting the racks to be 100 swung upwardly and parallel with the side walls of the car, with the ends of the planks 14 disposed intermediate of the bracket members 15 and the side walls of the car as shown in Figure 2.

The two stringer members 13, at the hinged 105 ends of the racks, namely the ends of the racks adjacent to the side walls and preferably at a point intermediate of the ends of the racks, are apertured to receive the bent ends or trunnion portions 18, 18 of a supporting member 19. The supporting member 19 which may be a single piece casting

is shown as preferably consisting of a metallic rod bent into the angular formation more clearly shown in Figure 2 and comprising the legs 20 and 21 whose ends constitute the 5 trunnions 18; the leg 20 extending substantially parallel with the stringers or spacing members 13, and of suitable length; while the leg 21 is given an inclination so as to extend from the spacing member 13 to which 10 it is pivotally connected into the plane of leg 20, at which point both leg portions 20 and 21 are shown bent substantially at right angles to leg 20 to provide a foot portion 22, of a length corresponding with the distance 15 between leg 20 and the main floor of the car.

The support is trunnioned on adjacent stringers 13, preferably in such manner that it will hang or extend substantially parallel with the lower surface of the rack when the 20 latter is lowered and at the same time will cause the support to automatically swing outwardly, through the action of gravity, to a supporting position or angle relative to the rack when the latter is raised into parallel relation with the side walls of the car, 25 with the foot portion 22 of the support resting on the main floor of the car.

In order that the support may not interfere with the rack resting properly on the 30 floor, the stringer or spacing member 13 in which the leg or side 20 of the support 19 is trunnioned, is notched or grooved as shown in dotted lines at 23 in Figure 3 at a point adapted to receive the foot 22 of the 35 support 19 when the latter has been swung or folded substantially parallel with the floor rack, namely into non-supporting position; and in order to prevent the support 19 swinging outwardly too far, one of the 40 stringers or spacing members 13 is shown provided with a stop pin or bolt 24 arranged in the member 13 on the side of the trunnion 18 opposite to that on which the notch or groove 23 is located.

45 With my improved support, when the floor racks are lifted into inoperative position, the support may be easily swung outward, thus permitting cleaning of the car or its use for other lading; the supporting elements being of such nature and construction as not to injure the lading or to interfere with the car insulation; while at the same time the floor-racks may quickly and easily be dropped into operative position by simply 50 shifting the support 19 into the folded position shown at the left in Figure 1 and in dotted lines in Figure 3.

I have shown and described what I believe is the simplest embodiment of my invention wherein the support is formed by bending a suitable metallic rod, but it is apparent that the support might be a single piece casting so formed and pivotally secured to the stringers as to swing outwardly 55 to a limited extent as previously described;

the invention having been described in terms employed merely as terms of description and not as terms of limitation, as the aforementioned structural modifications and others may be made without, however, departing from the spirit of my invention. 70

What I claim is:

1. In a refrigerator car, the combination of floor racks hingedly secured to the car floor adjacent to the side wall so as to swing 75 upwardly into inoperative position, with supporting means oscillatably mounted on the lower surface of the racks so as to extend lengthwise of the racks when the latter are in operative position and to swing outwardly from the racks when the latter are raised.

2. In a floor rack support, the combination of the spacing members or stringers of the rack, and a skeleton supporting member 85 or bracket journaled in the spacing members so as to swing outwardly at an angle to the floor rack when the latter is raised and to fold substantially parallel with and beneath the floor rack when the latter is lowered. 90

3. In a floor rack support, the combination of the spacing members or stringers of the rack, and a supporting member consisting of a single metallic rod, the ends whereof are bent in opposite directions and disposed in aligned sockets of two adjacent spacing members or stringers, while the intermediate portion of the rod is bent so as to provide a foot portion disposed transversely of the adjacent spacing member. 95

4. In a refrigerator car, floor racks pivotally secured so as to swing upwardly substantially parallel with the sides of the car, and a supporting member pivotally mounted on the lower side of each rack so as to normally fold substantially parallel with the floor racks and to swing outwardly at right angles to the floor racks when the latter are raised, and means for limiting the degree of swinging movement of the supporting member. 100

5. In a refrigerator car, floor racks provided with stringers or spacing members arranged in spaced relation intermediate of the sides and the longitudinal center line of the car, the ends of the racks adjacent to the car side walls being pivotally secured in place to permit the racks to be swung upwardly against the car side walls, the adjacent spacing members at the pivoted ends of the racks being provided with aligned apertures, a supporting member or rod having laterally disposed ends journaled in said apertures, while the intermediate portion of the rod is formed to provide a depending foot or car-floor engaging portion. 115

6. In a floor rack support, the combination of the spacing members or stringers of a rack, with a supporting member consisting of a metallic member having pivot providing 130

portions at opposite ends whereby said supporting member may be pivotally secured to adjacent stringers to extend substantially parallel with the lower side of the rack 5 when the latter is lowered and to automatically swing outwardly to a predetermined extent when the rack is raised, the free end of said member being provided with a floor engaging portion.

10 7. A floor rack support, consisting of a single rod bent into angular form with both ends of the rod arranged in substantial

alignment with each other and disposed in opposite directions to provide pivot-forming portions or trunnions adapted to enter sockets in adjacent stringers of the floor rack, while the intermediate portion of the rod is bent double and disposed substantially parallel with the ends of the rod to provide a floor engaging portion. 15
